United States Patent Office.

ALFRED HEALD, OF PHILADELPHIA, PENNSYLVANIA, ASSIGNOR TO
McCALLUM, CREASE & SLOAN, OF SAME PLACE.

Design No. 4,313, dated August 30, 1870.

DESIGN FOR A CARPET PATTERN.

The Schedule referred to in these Letters Patent and making part of the same

I, ALFRED HEALD, of Philadelphia, county of Philadelphia, State of Pennsylvania, have invented or produced a new and original Design for a Carpet Pattern, of which the following is a specification.

The figure in the accompanying drawing represents sufficient of a carpet pattern to illustrate my design, the main feature of which consists of a rustic fence-like figure, A, edged with and inclosing foliated ornaments, in addition to which there are medallion ornaments, B and C, all too clearly shown in the drawing to need explanation.

Irrespective of the colors employed—

I claim—

The design for a carpet pattern, substantially as described, and as illustrated in and by the accompanying drawing.

In testimony whereof I have signed my name to this this specification in the presence of two subscribing witnesses.

ALFRED HEALD.
